APPARATUS FOR THE MANUFACTURE OF
ARTIFICIAL THREADS OR FILAMENTSJoshua Bower, Spondon, near Derby, England,

9 Claims. (Cl. 18—8)

This invention relates to apparatus for the manufacture of artificial silk or other artificial threads or filaments and more especially to apparatus for the manufacture of artificial threads or filaments by the dry or evaporative method.

In the manufacture of artificial silk and the like, in which, as is known, the spinning solution is supplied under pressure to the jets or nozzles by pumps or other means, difficulty is experienced when a spinning jet or nozzle is required to be changed or replaced, removal of the jet or nozzle involving loss of pressure, waste of spinning solution and other inconveniences.

The object of the invention is to obviate or to overcome in a large measure these difficulties.

According to the invention I provide in apparatus for the spinning of artificial silk and the like (and especially in apparatus for the spinning of artificial silk and the like by the dry or evaporative method), a valve controlling the supply of the spinning solution to the jet or nozzle (referred to in the claims as the extrusion device), which valve is adapted to close or be closed automatically on the removal of the jet or nozzle, and to be automatically and mechanically opened by the act of fitting or replacing the jet or nozzle.

The valve may be constructed to cut off the supply of the spinning solution to the jet or nozzle entirely when in the closed position. I have found it preferable however to construct or arrange the valve so as in its "closed" position to allow a certain predetermined quantity of the spinning solution to escape, and especially to allow such a quantity to escape as ordinarily passes through the jet or nozzle when the jet or nozzle is spinning under the given pressure, or such a quantity as will ensure the pressure in the supply of the spinning solution remaining substantially constant. The valve and/or its seat may be grooved, slotted or otherwise suitably formed to give the desired passage of spinning solution when the valve is in the "closed" position. Preferably the valve is situated immediately behind the jet or nozzle.

According to one convenient form of the invention I provide a valve, which may be conical or of mushroom or of other type, working in a bore or passage of the pipe or other member to which the spinning jet or nozzle is fitted, the valve being adapted to close on to a seat formed in the said bore or passage on the removal of the spinning jet or nozzle. When the spinning jet or nozzle is fitted to the pipe or other member, it raises and supports the valve in the open position by means of the valve stem. The valve stem is constructed

to slide in the bore or passage referred to and act as a guide for the valve and is suitably formed or adapted to permit passage of the spinning solution. The lower end of the valve stem is preferably formed as a disc, ring or flange which has a sliding fit in the bore or passage referred to and which is formed with or presents one or more holes to permit passage of the spinning solution. In the claims, the disc, ring or flange is referred to as the guiding member. In such form, on the removal of the spinning jet or nozzle the valve will fall on to its seat and thereby cut off or restrict the flow of spinning solution. To ensure positive and quick closing of the valve a spring is preferably fitted between the top of the valve and an abutment above the same; for instance, when a filter-containing chamber is employed in the supply pipe or conduit above the valve, the filter may conveniently serve as such abutment.

The valve may be constructed to cut off the supply of spinning solution entirely when the jet or nozzle is removed; preferably, however, grooves or passages are formed in the face of the valve and/or on the face of the seat to enable a desired amount of spinning solution to escape when the valve is closed. For example, such grooves or passages may permit the escape of an amount such as to maintain substantially constant pressure in the supply of the spinning solution, or to allow such quantities of spinning solution to escape as are normally passed through the jet or nozzle in spinning.

One form of the invention is illustrated in the accompanying drawings, it being understood that this is given only by way of illustration and is in no way limitative. The form illustrated is especially useful in the spinning of artificial silk by the dry or evaporative method. In the example illustrated the valve is fitted in the lower part of a filter-containing chamber which terminates the supply pipe to which the jet or nozzle is fitted.

Figure 1 is a sectional view, with the valve in elevation, showing the nozzle or jet attached in position for spinning and the valve in the open position.

Figure 2 is a similar view but with the jet or nozzle removed and the valve in the closed position.

Figure 3 is a horizontal section on the line A—B Figure 2.

Figure 4 is a horizontal section on line C—D Figure 2.

Referring to the drawings, 1 indicates the

member forming the body of the cylindrical filter-containing chamber 2 which terminates the supply pipe to the spinning jet or nozzle and to which the jet or nozzle is attached, the member 1, shown broken away, terminating the supply pipe. The lower part of the body 1 is formed with a bore of relatively smaller diameter.

The spinning jet or nozzle 4 is attached (as shown in Figure 1) by screwing it on to the threaded end 5 of the member 1, the jet or nozzle being fitted with a packing ring 4a.

6 is a conical valve carried by the valve stem 7 working in the bore 3, and adapted to close on to a seat 8 formed at the top of the bore 3. The valve stem is guided in the bore 3 by a grooved upper collar or piston 9 and a lower ring or disc 10 the latter having holes 17, the collar 9 and ring or disc 10 both having a sliding fit in the bore 3.

20 In screwing on the spinning jet or nozzle it bears under the ring or disc 10 and raises the valve stem 7 and so lifts the valve 6 off the seat 8. If desired, one or more filter cloths may be interposed at any point between the jet or nozzle 4 and the ring or disc 10.

25 Grooves 18 are formed in the conical face of the valve 6, and a recessed chamber 3a is formed in the bore 3 beneath the seat 8, and the valve stem 7 is formed or provided at its lower part adjacent to the ring or disc 10, with a radially webbed or cruciform portion formed with slots 16.

30 When, as in Figure 2, the jet or nozzle 4 has been removed by unscrewing it, the valve 6 falls on to the seat 8, quick and positive closing of the valve being ensured by the spring 11 interposed between the top of the valve 6 and the bottom of the filter 12 in the chamber 2. The spring 11 fits into a recess in the bottom of the filter 12 and around a pin 13 formed on the top of the valve 6.

35 Assuming the apparatus to be spinning (see Figures 1, 3 and 4), the spinning solution passes laterally out through the filter walls 14 of the filter 12 into the chamber 2 which is filled with the solution under pressure. From the chamber 2 it passes between the valve 6 and seat 8 thence through the grooves 15 in the piston or collar 9, thence down the bore 3 and through the slots 16 in the radial webs 7a of the webbed portion of the valve stem 7, and through the holes 17 in the ring or disc 10 to the spinning jet or nozzle 4.

40 On the removal of the jet or nozzle, as explained above, the valve 6 closes on to its seat 8. The spinning solution now passes through the grooves 18 in the face of the conical valve 6, the grooves being so dimensioned that only a desired quantity of spinning solution will escape, for example, such as will maintain the pressure in the supply substantially constant or such as would ordinarily be extruded in spinning. From

the grooves 18 the spinning solution passes from the apparatus via the recessed chamber 3a and the grooves 15 in the piston or collar 9, down the bore 3, through the slots 16 of the radial webs 7a of the valve stem 7 and escapes through the holes in the ring or disc 10.

80 What I claim and desire to secure by Letters Patent is:—

1. In apparatus for the spinning of artificial silk and the like, the combination with an extrusion device for the spinning solution and means for supplying a spinning solution to the extrusion device, of a valve interposed between said supply means and the extrusion device and adapted to close or be closed automatically on the removal of the extrusion device, and to be automatically and mechanically opened by the act of fitting or replacing the extrusion device.

85 2. Apparatus as claimed in claim 1 having means for permitting a predetermined quantity of spinning solution to escape when the valve is in its closed position.

90 3. Apparatus as claimed in claim 1 wherein at least one of the members, i. e. the valve face and the valve seat, are formed with grooves or passages.

95 4. Apparatus as claimed in claim 1 in which the valve is held in its open position by the extrusion device.

100 5. Apparatus as claimed in claim 1 having a spring for bringing the valve to its closed position when the extrusion device is removed.

105 6. Apparatus as claimed in claim 1 having a pipe or member to which the extrusion device is attached and in which the valve is provided with a stem that slides in a bore of the pipe or other member and acts as a guide for the valve while providing a passage for the spinning solution.

110 7. Apparatus as claimed in claim 1 having a pipe or member to which the extrusion device is attached and wherein the valve is provided with a stem that slides in a bore of the member to which the extrusion device is fixed and acts as a guide for the valve while providing a passage for the spinning solution, the said stem being provided at its lower end with a guiding member sliding in said bore and having at least one hole for the passage of the spinning solution.

115 8. Apparatus as claimed in claim 1, and having means for permitting such quantity of spinning solution to escape when the valve is in the closed position as normally passes through the extrusion device when such device is spinning.

120 9. Apparatus as claimed in claim 1, and having means for permitting such quantity of spinning solution to escape when the valve is in the closed position that the pressure in the supply of spinning solution remains substantially equal to that obtaining during the normal spinning through the extrusion device.

125 JOSHUA BOWER.
